(57) **CLAIM**

I claim the ornamental design for a patio chair, as shown and described.

DESCRIPTION

FIG. 1 is a perspective view of a patio chair;

FIG. 2 is a front elevational view of FIG. 1; and,

FIG. 3 is a side elevational view of FIG. 1.

The patio chair is characterized by curved arms and crest design on the back.

1 Claim, 3 Drawing Sheets

FIG. 1

FIG. 2

FIG. 3
